COMBINED BRUSH AND SOAP HOLDER

Henry Lawrence Mills, Minneapolis, Minn.

Application May 27, 1949, Serial No. 95,665

2 Claims. (Cl. 15—105)

1

This invention relates to soap holders.

It is the general object of the invention to provide a novel and improved soap holder of cheap and simple construction which can be mounted as on a bathroom lavatory at a convenient location and which includes a bristle equipped brush, the bristles of which will be raised from the base of the brush so as to form a supporting surface on which a cake of soap may be placed to permit free drainage of soapy water from the soap and permitting the soap to dry after usage.

Another object is to provide such a soap holder wherein the bristles are so arranged that the upper edges of the bristles will form a concave supporting structure for the soap, thereby preventing the soap from slipping off the holder.

Another object is to provide such a soap holder which can not only be used to hold soap but may also be used as a nail or hand brush.

A further object is to provide such a soap holder which includes one or more sucker cups for ready mounting of the soap holder as on the surface of a lavatory.

The objects and advantages of the invention will more fully appear from the following description made in connection with the accompanying drawing wherein like reference characters refer to the same or similar parts throughout the several views, and in which

Fig. 1 is a plan view of a soap holder embodying the invention arranged for mounting on a vertical support, the supporting structure being shown in horizontal section;

Fig. 2 is a vertical section taken on the line 2—2 of Fig. 1 as indicated by the arrows;

Fig. 3 is a view in side elevation of the brush holder shown in Figs. 1 and 2 but showing the same arranged for mounting on a horizontal support, the support being shown in vertical longitudinal section;

Fig. 4 is an end view of the soap holder arranged as shown in Fig. 3;

Fig. 5 is a detail in enlarged scale showing portions of the soap holder illustrated in Figs. 1 to 4;

Fig. 6 is a vertical section taken on the line 6—6 of Fig. 5 as indicated by the arrows, one of the sucker cups being sectioned and the other sucker cup being shown in side elevation;

Fig. 7 is a plan view showing a different embodiment of the invention;

Fig. 8 is a vertical section taken on the line 8—8 of Fig. 7; and

Fig. 9 is a sectional view taken similar to Fig. 8 but showing a still different embodiment of the invention.

Referring first to the embodiment of the invention illustrated in Figs. 1 to 6, there is there shown a mounting plate such as base plate 10 which consists merely of a straight bar having a pair of apertures 10a adjacent its two ends within which rubber sucker cups 11 are mounted. The said sucker cups have grooved heads permitting the insertion of the heads through the apertures 10a upon compression of the upper portions of the heads until the grooved portions of the heads are received within the apertures 10a of the base 10. The central portion of the base 10 is formed to provide clamping ears 10b formed in pairs at the opposite edges of the base.

There is provided also a twisted wire brush core 12. This core is formed in oval shape to provide a brush head 12a and bristles 13 are secured by the core at the head portion 12a thereof, these bristles radiating out from the core in the usual manner of a wire brush. The brush head 12a will be horizontally disposed and thus the bristles at the inner portions of the head will project upwardly less distances than certain of the bristles outwardly disposed therefrom, and the upper ends of the bristles will thus form a supporting structure which is centrally dished or concavely curved to receive a cake of soap S in such manner as to be partially complementary to the convex surface of the usual soap cake. Accordingly, as a piece of soap S is supported by the brush formed by the twisted wire core head 12a and the bristles 13 the soap cannot slip off the brush and the many bristles will hold the cake of soap so as to permit drainage of soapy water therefrom, permitting the air to penetrate to the under side of the soap and dry it out.

The end portions 12b of the twisted wire core 12 are brought together and carried to the under side of the central part of the base 10, the parts 12c of the end portions of the core being bowed away from each other in a single plane to form a flat bearing against the under side of the plate 10 preventing the base from twisting to any appreciable extent relative to the twisted wire core. Beyond the bowed parts 12c the two end portions of the twisted wire core may be fastened together as by spot welds 14. The clamping ears 10b are crimped tightly around adjacent parts of the end portions of the twisted wire core and thus the twisted wire core is attached to the base 10.

There are shown portions of a lavatory L which has a horizontal surface 15 and a vertical surface 16. If it is desired to attach the soap holder as to a vertical surface of a lavatory or other support as illustrated in Figs. 1 and 2, the

twisted wire core is given a 90 degree bend at 17 between the end portions of the core attached to the plate 10 and the oval shaped head 12a. If, on the other hand, it is desired to mount the soap holder as on a horizontal surface 15, the twisted wire core is given a 180 degree bend as at 18 shown in Figs. 3 and 4.

To attach the soap holder in place it is merely necessary to press the sucker cups 11 tightly against the surface to which the holder is to be attached. When the holder is connected to a vertical surface it will present the appearance shown in Figs. 1 and 2, while when it is attached to a horizontal surface it will present the appearance as shown in Figs. 3 and 4. The bar of soap 15 S after use will be held without slipping by the bristles 13 and any loose water may freely drain from the soap and air can get to the bottom of the bar of soap to permit it to dry.

Referring to Figs. 7 and 8, there is there shown a slightly different embodiment of the invention. The soap holder there shown includes a brush base 19 having a number of apertures therein within which bristles 20 are located. The outer bristles rise to a greater height than the inner bristles so that the structure presented by the upper ends of the bristles will be convex as shown to readily receive the bar of soap S and prevent it from slipping as in the case of the first described structure. The base 19 is received by a block 21 of rubber or other resilient material, this block having an inwardly curled flanged portion 21a to fit around and grip the edges of the base 19. A pair of sucker cups 21b are formed at the lower side of the block 21.

In Fig. 9 a slightly different embodiment of the invention is illustrated. This device includes a brush base 22 within which upwardly extending bristles 23 are mounted and sucker cups 24 carrying screws 25 in their upper portions are attached by these screws to the under side of the base 22. As in the case of the soap holder shown in Figs. 7 and 8 the central bristles of the brush shown in Fig. 9 are of shorter length than the outer bristles to form the concavity for reception of the cake of soap.

It will be seen that a highly effective soap holder has been provided. The bristles not only act to hold a cake of soap in place at a convenient location, but they may be also used to clean the finger nails or the hands or for other brush purposes.

It will, of course, be understood that various changes may be made in the form, details, arrangement, and proportions of the various parts without departure from the scope of the present invention, which, generally stated, consists in the matter shown, and described, and set forth in the appended claims.

What I claim is:

1. A wire brush soap holder comprising a mounting member in the form of a stiff flat plate element, a plurality of suction cups connected with said plate for securely attaching the same to a smooth flat surface, a pair of laterally extending spaced wire clamping ears formed on an intermediate portion of said plate, an elongated wire brush having a bendable wire core having the intermediate portion thereof bent to form a generally annular soap-engaging and receiving member with an open central portion to engage only an intermediate portion of a cake of soap supported thereon, said wire core having end portions bent outwardly from the annular portion thereof and being received by said ears to be securely clamped in anchoring position on said plate thereby.

2. The structure set forth in claim 1 and the end portions of said wire core element being securely clamped together by said ears with the portions intermediate the ears being bowed outwardly away from each other to engage the adjacent surfaces of the plate and prevent twisting of the brush relative to the plate.

HENRY LAWRENCE MILLS.
